UNITED STATES PATENT OFFICE.

WILLIAM MITCHELL, OF MILWAUKEE, WISCONSIN, ASSIGNOR TO MITCHELL MANUFACTURING COMPANY, OF MILWAUKEE, WISCONSIN, A CORPORATION OF WISCONSIN.

SWING BOB.

Application filed March 15, 1926. Serial No. 94,814.

This invention relates to improvements in swing bobs.

It is one of the objects of the present invention to provide a novel form of swing for 5 playground installation for children.

A further object of the invention is to provide a swing having a unique motion and safe to children operating and using the same.

10 A further object of the invention is to provide a swing adapted to move in a horizontal plane at all times parallel with the ground.

A further object of the invention is to provide a swing device having an elongated seat 15 adapted to accommodate a plurality of children.

20 A further object of the invention is to provide a swing bob which is of very simple construction, is easy and smooth in operation, is easily installed, is strong and durable, and is well adapted for the purposes set forth.

With the above and other objects in view the invention consists of the improved swing 25 bob, and its parts and combinations as set forth in the claim, and all equivalents thereof.

In the accompanying drawing in which the same reference characters indicate the 30 same parts in all of the views:

Fig. 1 is a perspective view of the improved swing bob;

Fig. 2 is an enlarged detail view showing a bifurcated member which receives the upper ends of a pair of legs;

Fig. 3 is an enlarged end view of the seat showing its mounting;

Fig. 4 is a side view of the seat and mounting and on a larger scale, part being broken 40 away and shown in section;

Fig. 5 is a detail sectional view taken on line 5—5 of Fig. 4;

Fig. 6 is a cross-sectional view through the seat and illustrating the supporting arm for 45 the guard or back;

Fig. 7 is an enlarged detail view of the bearing arrangement for the swinging supporting arms; and

Fig. 8 is a sectional view thereof taken 50 on line 8—8 of Fig. 7.

Referring now more particularly to the drawing, it will appear that the numerals 10 indicate a pair of standards or supports from and between which an elongated seat is suspended. Each standard comprises two

5 pairs of downwardly diverging legs 11 adapted to be partially embedded in the ground. The legs are tubular in construction and the upper portions thereof fit into the shanks 12 of bifurcated joint members 13, set screws 14 also being provided. The upper end portions of the joint members also receive the ends of U-shaped top transverse tubular bars 16.

Projecting laterally inwardly from each 65 joint member is a pin 17 upon which is pivotally mounted a rocker link 18, held thereon by a cotter pin 19. Each rocker link is formed with a transverse bore 20 and a communicating groove 21 to receive the end portion of an arm 22, the extreme end portion of the arm being bent angularly to enter said bore. A U-bolt 23 further secures the arm to the rocker link.

The arms 22 are two in number and are 75 U-shaped and each arm supports the end portion of the elongated seat 24, as shown. The transverse portions of the arms are secured to the seat by means of tubular bearing brackets 25 secured to the undersurface 80 of the seat near each end, the arrangement of the bearing brackets being such that the arms may turn therein.

The seat 24 is braced longitudinally by a member 26 bolted against its undersurface, 85 as shown in Figs. 4, 5, and 6. To form a back or rail for the seat, an elongated rod 27 is provided, bent downwardly at its end portions and formed with looped portions 28 secured about the bearing brackets 25, as 90 shown in Fig. 3. The intermediate portions of the rail are braced by vertical supports 29 whose lower end portions are angular and bolted to the seat. The upper ends of the supports 29 are formed with clamps 30 to engage and receive the rail 27.

The swing, obviously, is a playground device especially designed for children and constructed so that they may not be readily injured thereby. There is ample clearance 100 between the seat edges and the supports to prevent striking the same and upper members 16 are arched so that a person may stand on the seat and not strike his head against one of said members. It will also be noted that the motion of the swing is unique in that the seat at all times remains in the same plane and parallel to the ground, and there can be no side movement of the same to 105 strike the standards.

From the foregoing description it will be seen that the improved swing bob is of very simple and novel construction, and is well adapted for the purposes described.

5 What I claim as my invention is:

In a playground apparatus, the combination with a plurality of socket members adapted to receive supporting elements, of pins projecting from said socket members, 10 an oscillating link pivotally and removably

mounted on each of said pins, each link being formed with a transverse bore and a communicating groove, suspension arms for said links engaging said grooves and having angular end portions entering said bores, and 15 U-bolts removably clamping the end portions of said arms to said links.

In testimony whereof, I affix my signature.

WILLIAM MITCHELL.
